UNITED STATES PATENT OFFICE.

HERMANN SCHULER, OF DUSSELDORF, GERMANY, ASSIGNOR TO RHEINISCHE METALL-
WAAREN- UND MASCHINENFABRIK, OF DUSSELDORF-DERENDF, GERMANY, A
CORPORATION OF GERMANY.

SHELL-FIRING GUN WITH TWO BARRELS.

Application filed November 25, 1924. Serial No. 752,206.

To all whom it may concern:

Be it known that I, HERMANN SCHULER, a citizen of Germany, residing at Dusseldorf, Germany, Holtkestr. 12, have invented 5 certain new and useful Improvements Relating to Shell-Firing Guns with Two Barrels, of which the following is a specification.

It is known to provide shell firing guns 10 with a short barrel of larger calibre (for high angle firing) and with a second barrel of smaller calibre and greater length for firing projectiles to a greater distance at low angle firing. In such cases it is very 15 important that both barrels should always be ready for use and for this purpose both barrels are provided with their own breech closing devices, and are always connected together; whereby one barrel then takes up 20 the recoil of the barrel in use. In the known arrangement by which both barrels are side by side or over one another on a common support, this mutual connection and the connection with the buffing and running out 25 devices is difficult to attain. Also, by their lateral disposition relatively to the middle plane of the gun and the great distance of the axes of the barrels from the axis of the buffing device of one or both barrels, torques 30 are set up which cause parts of the gun to be ununiformly stressed and are thus liable to reduce the accuracy of fire by the increased wear.

This invention is designed to obviate or 35 reduce these drawbacks by the arrangement in which the barrel of smaller calibre is disposed in the cradle carrying the barrel of larger calibre, and may be surrounded by the buffing and running out device of the latter and at the same time form the piston rod for these devices.

The accompanying drawings represent examples of the invention in a barrel recoil gun with two barrels *a* and *e* which are always ready for firing, which have a single air running out device comprising a displacer and a compressed air container.

Figure 1 shows a side elevation of the gun partly in section; and

Figure 2 is a cross section;

Figure 3 shows a detail on a larger scale.

In the gun illustrated, during the barrel recoil the air in the container *b* is com-

pressed by a liquid displaced by a piston *e'* and stores up the energy necessary for running out the barrel. Between the displacer piston *e'* and the compressed air container *b* there is a throttling device *f* for altering the area of the openings for the passage of the liquid during the recoil, so that on the recoil movement of the barrel on firing, the passage of the fluid from the displacer cylinder *d* into the running out cylinder *h* is controlled in the manner usual with liquid buffers.

The smaller barrel *e* forms the piston rod of the piston *e'*. It is mounted in and surrounded and guided by the displacer cylinder. By this arrangement the vertical dimensions of the gun are not increased as compared with that of a gun with only one barrel disposed over the buffing and running out device. The usual connecting means between the barrel and the piston rod of the buffer are provided for connecting the two barrels together.

The barrel *a* of greater calibre is supported and guided on the container *b*. The thin walled hollow container *b* is pivoted on horizontal trunnions *b'* in the carriage *c*. In the container *b* is the cylinder *d* which is open at both ends and which tightly closes the compressed air container both in front and rear.

The barrel *e* of smaller calibre carries at 85 its forward part the piston *e'* formed as a stuffing box and mounted so as to be longitudinally displaced by this piston in the cylinder *d*. The air container *b* is connected with the interior of the cylinder *d* by openings *d'* provided at the rear part of the cylinder. In the arrangement shown in Figure 1 the larger barrel *a* is rigidly connected by claws on its breech *a'* with the breech *a''* of the smaller barrel *e*.

In the firing position, both barrels take up the position for buffing and running out shown in Figure 1. The space behind the piston *e'* of the cylinder *d* is completely filled with liquid, while the level of the liquid in container *b* is higher than the openings *d'* in the cylinder *d*. The action of the buffing and running out device needs no further explanation, as it is unessential for the invention. Obviously, the invention can also be applied to guns which have a buf-

fer separate from the running out device, in which case the smaller barrel *e* can form either the piston rod of the buffer or that of the running out device.

5. It has been assumed that the barrel *e* of the smaller calibre forms the piston rod of the buffering and running out device. The arrangement can, however, be such that it is inserted in the buffering and running out device with the provision of a separate piston rod; also, it may be only surrounded by the cradle of the larger barrel *a*, the buffering and running out device being arranged laterally.

If both barrels are rigidly connected, 15 bending stresses occur in the connecting breech *e*², on firing from the smaller barrel *e*, since the larger barrel *a* imposes in consequence of its great mass considerable resistance to a rapid acceleration. If the barrels 20 are spring connected by metal or rubber springs, as shown in Figure 3, the recoil movement of the smaller barrel is transmitted without shock to the larger barrel which is gradually brought up to the speed 25 of the smaller barrel, while when firing from the larger barrel, the smaller barrel is immediately taken with it.

I claim:

1. A shell firing gun comprising two interconnected barrels of different calibre, one barrel being provided with a buffering device for the other barrel.
2. A shell firing gun comprising two interconnected barrels of different calibre, one barrel forming a running out device for the other barrel.

3. In a shell firing gun with two barrels of different calibre of the kind described in which the barrel of smaller calibre forms 40 a piston rod for a buffering device for the barrel of greater calibre.

4. In a shell firing gun with two barrels of different calibre of the kind described in which the barrel of smaller calibre forms 45 a piston rod for a buffering device for the barrel of smaller calibre.

5. In a shell firing gun with two barrels of different calibre of the kind described in which the barrel of smaller calibre forms 50 a piston rod for a running out device for the barrel of greater calibre.

6. In a shell firing gun with two barrels of different calibre of the kind described in which the barrel of the smaller calibre forms 55 a piston rod for a running out device for the barrel of smaller calibre.

7. In a shell firing gun with two barrels of different calibre of the kind described in which the barrel of smaller calibre forms 60 the piston rod of the buffering device.

8. In a shell firing gun with two barrels of different calibre of the kind described in which the barrel of smaller calibre forms the piston rod of the running out device.

65 9. In a shell firing gun with two barrels

of different calibre of the kind described in which the barrel of smaller calibre is spring connected to the barrel of greater calibre by elastic means, so that on firing from the barrel of smaller calibre, the barrel of larger 70 calibre is gradually brought without shock to the same speed as the recoiling barrel of smaller calibre.

10. A shell firing gun comprising two interconnected barrels of different calibre, one 75 barrel being provided with a buffering device.

11. A shell firing gun comprising two interconnected barrels of different calibre, one barrel forming a running out device.

12. A shell firing gun comprising two interconnected barrels of different calibre, one barrel forming the piston rod of a buffering device.

13. A shell firing gun comprising two interconnected barrels of different calibre, one 85 barrel forming the piston rod of a running out device.

14. A shell firing gun comprising two interconnected barrels of different calibre, one barrel forming the piston rod of a buffering device for the other barrel.

15. A shell firing gun comprising two interconnected barrels of different calibre, one barrel forming the piston rod of a running 95 out device for the other barrel.

16. A shell firing gun comprising two interconnected barrels, one barrel forming the piston rod of a buffering device.

17. A shell firing gun comprising two interconnected barrels, one barrel forming the 100 piston rod of a running out device.

18. A shell firing gun comprising two interconnected barrels, one barrel forming the piston rod of a buffering device for the other barrel.

19. A shell firing gun comprising two interconnected barrels, one barrel forming the piston rod of a running out device for the other barrel.

20. A shell firing gun comprising a barrel; a piston mounted on said barrel; a displacer cylinder mounted around said barrel and in which said piston operates; and a second barrel mounted on said first-named barrel whereby said piston will act as a 110 buffering device for both of said barrels.

21. A shell firing gun comprising a barrel; a piston mounted on said barrel; a displacer cylinder mounted around said barrel and in which said piston operates; a container for said cylinder; and a second barrel mounted on said first-named barrel and adapted to have its front end slide on said container, said piston acting as a buffering device for both of said barrels.

22. A shell firing gun comprising a barrel; a piston mounted on said barrel; a displacer cylinder mounted around said barrel and in which said piston operates; and a second barrel resiliently mounted on said 120 130

first-named barrel whereby said piston will act as a buffing device for both of said barrels.

23. A shell firing gun comprising a barrel; a piston mounted on said barrel; a displacer cylinder mounted around said barrel and in which said piston operates; and a second barrel resiliently mounted on said first-named barrel and adapted to have its front end slide on said container, said piston and liquid acting as a buffing device for both of said barrels.

24. A shell firing gun comprising a barrel; a piston mounted on said barrel; a displacer cylinder mounted around said barrel and in which said piston operates and having openings therein at the rear end; and a container surrounding said cylinder, said cylinder and container being adapted to be filled with a liquid to just cover the openings in said cylinder thus acting as a buffing medium for the barrel when fired.

25. A shell firing gun comprising a barrel; a piston mounted on said barrel; a displacer cylinder mounted around said barrel and in which said piston operates and having openings therein at the rear end; a container surrounding said cylinder, said cylinder and container being adapted to be filled with a liquid to just cover the openings in said cylinder thus acting as a buffing medium for the barrel when fired; and a throttling device for said openings.

35 26. A shell firing gun comprising a barrel; a piston mounted on said barrel; a displacer cylinder mounted around said barrel and in which said piston operates and having openings therein at the rear end; a container surrounding said cylinder, said cylinder and container being adapted to be

filled with a liquid to just cover the openings in said cylinder; and a second barrel mounted on said first named barrel and adapted to have its front end slide on said container, said piston and liquid acting as a buffing device for both of said barrels.

27. A shell firing gun comprising a barrel; a piston mounted on said barrel; a displacer cylinder mounted around said barrel and in which said piston operates and having openings therein at the rear end; a container surrounding said cylinder, said cylinder and container being adapted to be filled with a liquid to just cover the openings in said cylinder; a throttling device for said opening; and a second barrel mounted on said first named barrel and adapted to have its front end slide on said container, said piston and liquid acting as a buffing device for both of said barrels.

28. A shell firing gun comprising a barrel; a piston mounted on said barrel; a displacer cylinder mounted around said barrel and in which said piston operates and having openings therein at the rear end; a container surrounding said cylinder, said cylinder and container being adapted to be filled with a liquid to just cover the openings in said cylinder; a throttling device for said openings; and a second barrel mounted on said first named barrel and adapted to have its front end slide on said container, said piston and liquid acting as a buffing device for both of said barrels, and said barrels being pivotally supported on a carriage by means of said container.

In testimony whereof I have affixed my signature.

HERMANN SCHULER.
